UNITED STATES PATENT OFFICE.

EMIL SWANSON, OF STEGER, ILLINOIS, ASSIGNOR TO STEGER & SONS PIANO MANUFACTURING COMPANY, OF STEGER, ILLINOIS, A CORPORATION OF ILLINOIS.

TRANSPOSING MECHANISM FOR AUTOMATIC PLAYERS.

1,179,677.

Specification of Letters Patent.

Patented Apr. 18, 1916.

Application filed July 31, 1914. Serial No. 854,229.

To all whom it may concern:

Be it known that I, EMIL SWANSON, a citizen of the United States, residing at Steger, in the county of Will and State of Illinois, 5 have invented new and useful Improvements in Transposing Mechanism for Automatic Players, of which the following is a specification, reference being had to the accompanying drawings, forming a part thereof:

10 The purpose of this invention is to provide an improved construction of the tracker and roll carriage of an automatic piano player mechanism, adapted for the purpose of transposing the music.

15 It consists in the elements and features of construction shown and described, as indicated in the claims.

In the drawings: Figure 1 is a front elevation of a structure embodying this invention. Fig. 2 is a section at the line 2—2, on Fig. 1. Fig. 3 is a section at the line 3—3, on Fig. 2. Fig. 4 is a section at the line 4—4, on Fig. 1. Fig. 5 is a section at the line, 5—5, on Fig. 4.

20 The structure shown in the drawings comprises a tracker box, A, which is adapted to be mounted in any usual manner upon any convenient support in the piano casing, as, for example, upon the transversely-extending support board, X, which may be supported upon the piano casing at its ends and any intermediate points by blocks or brackets, not shown. The tracker bar, B, having the player apertures only,—not including 25 any apertures for controlling stops or automatically modifying the action in any way,—is mounted rigidly upon the tracker box in any convenient manner, as by the bracket member, C, having its extended 30 ends, C¹, secured to the rear edges of the end boards of the tracker box, and having the arms, C², intermediate its ends extending forward to reach the rear face of the tracker bar, and at their forward ends turned 35 inward for attachment to the back side of the tracker bar at the ends thereof, as shown by the securing screws, e. The roll carriage 40 comprises flat metal end bars, D, D¹, and longitudinal members, D² and D³, connecting the corresponding ends of the end bars 45 so as to form a four-square rigid frame. These longitudinal members preferably 50 comprise rods, d², d², and spacing tubes, D⁴ and D⁴, on the rods between the end bars, D and D¹, said end bars being clamped

tightly against the ends of the spacing tubes by nuts, d³. The end bars, D and D¹, are accommodated in the channels, a, formed on the inner faces of the end boards, A¹ and A², of the box, A, and the length of the 60 spacing tubes, D⁴, D⁴, of the longitudinal members of the roll carriage is such with respect to the length of the tracker box that the end bars, D, D¹, can play in the grooves, a, substantially the full depth of the groove,— 65 that is to say, the roll carriage can be moved longitudinally with respect to the tracker box for a distance at least equal to the depth of the said grooves, a. The rods, d², of the longitudinal members of the roll 70 carriage extend through the right hand end board of the tracker box and are additionally connected together by a right hand end bar, D⁵, which is spaced from the bar, D¹, by spacing tubes, d⁶, on the rods, d², between said two bars, or more exactly speaking, between the bar, D⁵, and the nuts, d³, which are bound against the outer side of the bar, D¹. Similar binding nuts, d⁷, are 75 applied upon the outer threaded ends of the rod, d², to clamp the outer bar, D⁵, against the ends of the spacing tubes, d⁶. The roll driving train comprises shafts and wheels supported on the bars, D¹ and D⁵, and requiring no particular description except for certain preferential features hereinafter 80 mentioned. The motor which may be any customary form of air motor, conveniently represented at E, is mounted upon the supporting bar, X, at the right hand end of the 85 tracker box and roll carriage having its driving sprocket wheel, F, substantially in the plane of the initial sprocket wheel, F¹, of the roll driving train, said two sprocket 90 wheels being connected by a chain in the customary manner which permits lateral adjustment of the driven wheel with respect to the driving wheel to considerable extent 95 without interfering with the transmission of motion from the driving to the driven wheel. 100

The roll carriage has a forked arm, G, extending forward from its left hand end bar, D, engaging the groove, h, formed in the shank of an adjusting thumb screw, H, which has its shank mounted for rotation and longitudinal movement in a bearing, J, provided for it on the right hand end board of the tracker box. Said thumb screw is reduced at its left hand end and has its re- 110

duced portion, J^4 , threaded for engagement with a bracket, K , apertured and threaded to receive it, and mounted upon the outer side of said end board, having its threaded 5 end portion offset from the outer side of the board for a distance equal substantially to the lateral play of the bars, D , D^1 , of the roll carriage in the grooves, a , of the tracker box. The knurled head, H^1 , of this thumb 10 screw stands exposed at the inner side of the left hand end of the tracker box just below and in front of the take-up roll, L , where it is in convenient position to be reached by the hand of the operator for adjusting the roll carriage right or left by turning the thumb screw one direction or another.

To the end bars, D and D^1 , of the roll carriage by brackets, M^2 , M^2 there are secured rigidly for movement with said roll carriage tracker bar terminals, M , M , preferably rigidly connected together and spaced apart by a tie bar, M^1 , and which are provided with rigidly projecting dowels, m , to receive which the ends of the tracker bar, B , are bored so that the said tracker bar and tracker bar terminals are maintained in perfect alinement with the range of sliding of the terminals with respect to the bar equal to the range of play of the roll carriage end 20 bars, D , in the ends of the tracker box. These tracker bar terminals, M , are provided with the customary apertures, m^1 , for connection by the tubes, m^2 with pneumatic devices for automatically adjusting the spool 25 centers to keep the note-sounding perforations of the note sheet accurately alined with the note-sounding tracker apertures. Mounted upon the roll carriage by means of the rigid post, R , are the pneumatic devices for 30 such adjustment comprising primary vacuum chamber, P , to which, for connection with the primary pneumatics therein (not shown) the tube, m^2 , leads for controlling the binary motor pneumatics, Q , Q , and the 35 connecting rod, S , from the moving members of the binary pneumatics, said rod extending through the tracker box end boards and roll carriage bars, D , D^1 , and D^2 , to the right hand end of the roll carriage for 40 connection with the cam or crowding device, S' , which operates upon the spindle, T , of the spool live center for adjusting the spool in the manner well understood. A bracket, W , bound rigidly to the post, R , serves to 45 support the chamber, P , on the post and thereby on the roll carriage. Binary pneumatics of the said pneumatic spool adjusting action are mounted on and carried with the chamber, P .

50 The roll driving train comprises the driven wheel, F^1 , on the shaft, f , and on the same shaft a take-up pinion, F^{10} , and re-wind sprocket wheel, F^2 , both said pinion and sprocket wheel being loose for rotation 55 on the shaft and adapted to be actuated by

means of a clutch, F^3 , which is feathered on the shaft for sliding thereon in rotation therewith, and which is shiftable into engagement with the pinion, F^{10} , or the sprocket wheel F^2 by means of the shift 60 lever, F^4 , actuated by the rod, F^5 , whose operating connection is not shown. On the spool live center spindle, T , there is mounted rigidly the sprocket wheel, T^1 , for connection by a driving chain, not shown, with the 65 sprocket wheel, F^2 , and on the same spindle there is mounted a brake drum, T^2 , which is in the same plane with a brake drum, T^3 , on the take-up roll shaft, and rigid therewith alongside of the main gear, T^4 , on said 70 shaft which is actuated by the pinion, F^{10} . A brake bar, V , mounted for sliding vertically as a brake shoe, V^1 , for engaging the drum, T^2 , on its upper side, and a brake shoe, V^2 , for engaging the drum, T^3 , on its 75 lower side, and on the lower end of the brake bar it has a foot, V^3 , which is encountered by a cam arm, J^4 , which projects from the shift lever, F^4 , in position of encounter of said cam arm and cam foot when 80 the shift lever is moved for engaging the clutch, F^3 , with the re-wind sprocket wheel, F^2 . In such encounter the brake bar is lifted and the brake shoe, V^2 , is brought into engagement with the brake drum, T^3 , the other 85 brake shoe, V^3 , being at the same time lifted out of contact with the brake drum, T^2 , on the spool spindle. A spring, V^4 , is preferably provided for thrusting the brake bar downward so as to apply pressure in addition to that afforded by gravity for engagement of the brake shoe, V^1 , with the drum, T^2 , when the brake bar is at the lower position. Both the brake shoes, V^1 and V^2 , are 90 felt covered and afford silent and suitably 95 mild braking action for playing and re-winding.

When the structure above described is in operation with the perforated note sheets traveling over the tracker, B , from the spool 100 to the take-up roll, the opposite marginal edges of the note sheet cooperating with the tracker duct, m^1 , in the tracker end members in a well understood manner, causes the binary pneumatics, Q , to operate either for 105 thrusting or for pulling the rod, S , to cause the cam, S' , either to withdraw from the end of the shaft, E , permitting the spool, W , to yield to the right or to push it to the left as necessary to correct the displacement of 110 the note sheet on the tracker bar. It will be understood that the proper alinement of the perforations of the note sheet with the apertures of the fixed or main tracker bar member, B , will be obtained initially by rotating the screw, H , which by its engagement shown in Figs. 4 and 5 with the forked arm, G , on the roll carriage side bar, D , causes said roll carriage to be moved horizontally to the right or left according to the 115 120 125 130

direction of rotation of the screw. It will be observed also that the same expedient makes it possible for the operator to adjust the roll carriage, and thereby the note sheet, 5 not only for alinement of its perforations with the main tracker member apertures, but also for shifting the registration one or more steps for transposition of the music; and it will be understood that the range of 10 adjustment provided for by the spacing of the tracker end member, M, with respect to the length of the fixed tracker member, B, may be such as to permit any desired number of steps of transposition in the manner desired.

I claim:—

1. In combination with a fixed tracker and roll box, a main tracker member having the note-controlling apertures mounted fixedly with respect to the tracker box; a roll carriage mounted for movement with respect to the tracker box in the direction of the roll axes, and tracker end members mounted rigidly with the roll carriage alined with the 25 main tracker member, and means for adjusting the roll carriage with respect to the tracker box in the direction of length of the tracker.

2. In combination with a fixed tracker box; a main tracker member rigid therewith; tracker end members alined with the main tracker member; a roll carriage mounted in the tracker box movable in the direction of the roll axes; means for so moving it; tracker end members rigid with the roll carriage alined with the main tracker member, the main tracker member having the tracker mouths for connection with the note-playing devices, and rigid tubes leading 30 from such mouth; the tracker end members having mouths for controlling mechanical adjustments; pneumatic adjustment controlling devices mounted on the roll carriage and carried therewith in the movements of 35 the latter, and tubes leading from the tracker end member mouths to said pneumatic devices.

3. In combination with a fixed tracker and roll box, a main tracker member rigid therewith; a roll carriage mounted in the box movable in the direction of the axis of the rolls; tracker end members rigid with the roll carriage alined with the main tracker member at opposite ends thereof; 50 and a bar extending alongside the main tracker member and rigidly connecting the tracker end members, and means for adjusting the roll carriage longitudinally with respect to the main tracker member.

4. In combination with a fixed tracker 60 box; a main tracker member rigid therewith; a roll carriage mounted in the tracker box movable in the direction of the roll axes, and means for adjusting it relatively to the tracker box; tracker end members rigid with 65 the roll carriage alined with the main tracker member, and guide pins extending longitudinally from the opposite ends of the main tracker member into the tracker end members to guide them longitudinally and 70 preserve their alinement with the main tracker member.

5. In combination with a fixed tracker box; a main tracker member rigid therewith; a roll and roll-driving-train carriage, 75 comprising three parallel bars, and longitudinal bars connecting them rigidly; means for spacing the parallel bars from each other; the tracker box having its vertical side members channeled on their inner surfaces, two of the roll carriage bars being positioned in said channels and the third being positioned entirely outside the box; a roll-driving train having its shafts and gears mounted in said carriage between the last 80 mentioned bar and the approximate side of the box, and means mounted on one of the tracker box side members engaging one of the roll carriage side bars, said means being manually operable for adjusting the roll 85 carriage relatively to the tracker box.

6. In combination with a roll carriage, which is fixed as to vertical position, a roll-driving-train mounted therein, comprising shafts for rotating the take-up roll and the 90 spool live center; brake drums on said shafts respectively, located in substantially the same vertical plane transverse to the shafts; a brake bar mounted movably on the roll carriage extending in said plane; brake 95 shoes on said bar at opposite sides respectively of the drums; a reversing lever and a cam bar thereon; the brake bar having a cam projection positioned for engagement by the cam bar in the reversing movement of 100 the lever, said cam bar and cam projection being relatively formed to coöperate upon their engagement for shifting the brake bar to reverse the application of the brakes upon the drum respectively.

In testimony whereof, I have hereunto set my hand at Steger, Illinois, this 27th day of July, 1914.

EMIL SWANSON.
